TOILET BOWL FLUSH TANK DISINFECTANT CONTAINER

Antone Nunes Vierra, Honolulu,
Territory of Hawaii

Application August 29, 1950, Serial No. 182,070

2 Claims.

(Cl. 4—227)

This invention relates to containers for disinfectants particularly of the type used in flush tanks of toilet bowls, and in particular a tank having an outlet nipple in the lower end with threaded nipple on the upper end aligned with the outlet nipple and having a cap with a valve suspended by a valve stem from the cap and positioned to coact with the outlet nipple, a threaded filling nipple having a cap thereon positioned in the upper end of the tank, and a vent tube extended from the outlet nipple below the lower end of the tank to a point corresponding with the upper end of the tank.

The purpose of this invention is to provide an improved vent for a disinfecting container for flush tanks of toilet bowls wherein a small charge of disinfectant is dispensed with the flushing of the bowl.

Various types of devices have been provided for supplying disinfectant to flush tanks of toilet bowls and to the bowls direct and some of these are actuated by the rise and fall of water in the tank but it has been found difficult to provide a vent that permits a small quantity of air to replace disinfectant in the container that operates with each flushing of the tank. With this thought in mind this invention contemplates a disinfectant containing tank having a small tube providing a vent extended from a point just below the valve seat in an outlet nipple of the tank to a point adjacent the upper end of the tank above the high water level of the flush tank.

The object of this invention is, therefore, to provide means for forming a vent in a disinfectant container for flush tanks of toilet bowls wherein air is admitted to the disinfectant container from a point above the high water level with water in the flush tank.

Another object of the invention is to provide a disinfectant container for flush tanks of toilet bowls that may be installed in tanks now in use without changing the design or construction thereof.

A further object of the invention is to provide an improved vent tube or disinfectant container for flush tanks of toilet bowls which is of a simple and economical construction.

With these and other objects and advantages in view the invention embodies a disinfectant container having a depending outlet nipple or spout with a valve in the upper end of the spout and with a small vent tube connected to the nipple and spaced from and extended upwardly on the outer surface of the wall thereof with the

5 tube secured to the wall at spaced points and with the upper end of the tube extended to a point corresponding with the upper end of the tank.

10 Other features and advantages of the invention will appear from the following description taken in connection with the drawings wherein:

Figure 1 is a cross section through the flush tank of a toilet bowl showing the position of 15 the disinfectant container therein.

Figure 2 is a vertical section through the disinfectant container or tank showing the vent tube on one side thereof and with the tube shown in elevation.

20 Figure 3 is a detail on an enlarged scale illustrating the connection of the lower end of the vent tube with the outlet nipple or spout of the tank.

Referring now to the drawings wherein like 25 reference characters denote corresponding parts the improved disinfectant tank of this invention includes a tank 10 having an outlet spout 11 at the lower end, a threaded nipple 12 on the upper end and aligned with the outlet spout, a filling nipple 13, a valve 14, and a vent tube 15.

In the design shown, the valve seat 16 is provided around the upper end of the spout 11 and the lower conical shaped surface 17 of the valve 14 coacts with the seat 16 to close the lower end of the tank when the device is in an inoperative position. When the device is set for use the valve 14 is actuated by a head 18 on the valve stem 19 which is threaded through a lug 20 on the inner surface of a cap 21 whereby the surface 17 is positioned slightly above the seat 16 so that a small opening is provided around the upper end of the spout in the lower end of the tank.

The stem 19 is provided with a lock nut 22 whereby with the parts adjusted to provide a desired opening in the valve elements the nut 22 is turned against the lower end of the lug 20 to retain the parts in position.

40 The filling nipple 13 is provided with a closure cap 23 and the container may be provided with a hook 24 by which it may be suspended from a wall 25 of a flush tank as indicated by the numeral 26. The tank or container 10 is held by bands 27 and 28 on the hook 24 and it will be understood that the tank or container may be suspended in the flush tank by any means or in any suitable manner.

45 The vent tube 15 opens into the spout 11 through an orifice 29, as shown in Figure 3 and the tube may be attached to the outside of

the wall of the tank by lugs 30, 31 and 32 as shown in Figure 2 or may be incorporated therein as may be desired.

With the parts arranged in this manner the tank or container 10 is positioned in a flush tank of a toilet bowl or the like and with the valve 14 adjusted from the upper end of the stem 19, a comparatively small opening is provided in the lower end of the tank. With water in the tank extended upwardly above the lower part of the tank or container 10, disinfectant is sealed in the tank and as the water level drops below the lower end of the opening 29 of the vent 15, air is admitted to the container 10 whereby a small amount of disinfectant is permitted to drop downwardly through the spout or nipple 11 and into water in the tank.

The container 10 may be refilled without disturbing the valve 14, through the nipple 13 with the cap 23 removed.

It will be understood that modifications may be made in the design and arrangement of the parts without departing from the spirit of the invention.

What is claimed is:

1. In a flush tank disinfectant container, the combination which comprises a tank having a depending outlet nipple on the lower end with a valve seat in the upper end of the nipple, a valve positioned to coact with the valve seat, a threaded nipple on the upper end of the tank aligned with the outlet nipple, a valve stem on the lower end of which the valve is carried extended through the threaded nipple on the upper end of the tank, a cap threaded on the said threaded nipple on the upper end of the tank through which the valve stem extends, and means adjusting the position of the valve stem in said cap, and a vent tube arranged exteriorly of said tank and having its lower end communicating with the upper portion of said spout be-

low the valve seat and having its upper end terminating above the top of said tank.

2. In a flush tank disinfectant container, the combination which comprises a tank having a plurality of threaded nipples positioned on the upper end and having an outlet spout extended downwardly from the lower end and aligned with one of the said threaded nipples on the upper end, a vent tube extended from the upper end of the outlet nipple to a point above and exteriorly of the upper end of the tank and communicating with the upper end of the said outlet nipple, caps threaded on the threaded nipples on the upper end of the tank, a valve stem threaded in the cap of the nipple aligned with the outlet spout and having a valve member on the lower end positioned to coact with the upper end of the outlet spout, and means locking the valve stem in adjusted positions, said vent tube being arranged exteriorly of said tank and having its lower end communicating with the upper portion of said spout and having its upper end terminating above the top of said tank.
